[57] CLAIM

The ornamental design for a beach chair, as shown and described.

DESCRIPTION

FIG. 1 is a perspective view of a beach chair showing my new design;

FIG. 2 is a right elevational view of a beach chair thereof; the left elevational view being identical in appearance;

FIG. 3 is a front elevational view thereof;

FIG. 4 is a rear side elevational view thereof;

FIG. 5 is a top plan view thereof; and,

FIG. 6 is a bottom plan view thereof.

The fragmented cross-hatching shown on the seat and backrest is understood to represent fabric which would be continuous throughout the implied areas.

FIGS. 2 through 6 have been shown on a reduced scale with respect to FIG. 1.
